Primary Examiner—Doris V. Coles
Attorney, Agent, or Firm—Anthony G. Eggink[57] **CLAIM**

The ornamental design for a mouse trap receptacle, as shown and described.

DESCRIPTION

FIG. 1 is a top plan view of a mouse trap receptacle, showing my new design in a closed position;

FIG. 2 is a side elevational view thereof in an open position;

FIG. 3 is a front elevational view thereof in an open position, the rear view being a mirror image thereof;

FIG. 4 is a bottom plan view thereof; and,

FIG. 5 is a side elevational view opposite that of FIG. 2.

FIG. 1

FIG. 2

FIG. 3

FIG. 4

FIG. 5
